CLAIM

I claim the ornamental design for a cup holder for temperature control, as shown and described.

DESCRIPTION

FIG. 1 is a perspective view of our design;

FIG. 2 is a front view of our design;

FIG. 3 is a rear view of our design;

FIG. 4 is a first side view of our design;

FIG. 5 is a second side view of our design;

FIG. 6 is a top view of our design;

FIG. 7 is a bottom view of our design; and,

FIG. 8 is a perspective view illustrating a state in which fixing wings for fixing the cup holder are opened.

The subject design is a cup holder for temperature control capable of heating or cooling contents of a cup by inserting the cup into an inner space of the cup holder.
